UNITED STATES PATENT OFFICE.

CHARLES D. MONTAGUE, OF NEW YORK, N. Y., ASSIGNOR TO MOTOR ROLLING CHAIR COMPANY, A CORPORATION OF NEW YORK.

DESIGN FOR A ROLLING-CHAIR BODY.

No. 39,547.

Specification for Design.

Patented Sept. 15, 1908.

Application filed July 2, 1908. Serial No. 441,716. Term of patent 7 years.

To all whom it may concern:

Be it known that I, CHARLES D. MONTAGUE, a citizen of the United States, residing at the borough of Brooklyn, city of New York, in the county of Kings and State of New York, have invented a certain new, original, and ornamental Design for Rolling-Chair Bodies, of which the following is a specification, reference being had therein to the accompanying drawings, forming part thereof.

Figure 1 is a side elevation of a rolling-chair body showing my new design. Fig. 2 is a rear elevation of the same. Fig. 3 is an inverted plan view of the same.

I claim:

The ornamental design for a rolling-chair body as shown.

CHARLES D. MONTAGUE.
